UNITED STATES PATENT OFFICE.

SETH W. JOHNSON, OF NEW YORK, N. Y.

DESIGN FOR A BANNER.

SPECIFICATION forming part of Design No. 14,846, dated March 4, 1834.

Application filed December 12, 1833. Term of patent 14 years.

To all whom it may concern:

Be it known that I, SETH W. JOHNSON, a citizen of the United States, residing at New York, in the county and State of New York, 5 have invented and produced a new and original Design for a Banner, of which the following is a specification, reference being had to the accompanying drawing.

This design relates to a banner composed of 10 a field containing a number of stars, and a second field which is ornamented by horizontal bars or stripes, and which contains an inner space or field.

The accompanying drawing represents a face 15 view of my banner.

In this drawing, the letter A designates a space or field situated in the interior of the field B, which is ornamented by a number of horizontal bars or stripes, C C, of different 20 color. The remaining field, D, of this banner is ornamented by a number of stars.

My design is intended particularly for the

American banner, in which the field D is blue and the stars contained therein are white. The stripes C C are alternately red and white, and 25 the inner field, A, intersects a number of these stripes, so that it imparts to the banner a novel and distinguishing appearance.

What I claim as new, and desire to secure by Letters Patent, is— 30

The design for a banner, consisting of the field B, having stripes C, the corner-field D, having the stars, and the field-space A, intersecting and breaking some of the stripes intermediate of their ends at one side of the field 35 D, as shown and described.

In testimony whereof I have hereunto set my hand and seal in the presence of two subscribing witnesses.

SETH W. JOHNSON. [L. S.]
